CLAIM

The ornamental design for a wireless conference apparatus,
as shown and described.

DESCRIPTION

FIG. 1 is a right top perspective view of a wireless conference apparatus showing the new design;

FIG. 2 is a right side elevational view thereof;

FIG. 3 is a top plan view thereof;

FIG. 4 is a front elevational view thereof;

FIG. 5 is a left side elevational view thereof; and,

FIG. 6 is a rear elevational view thereof.

The broken line showing on FIGS. 1 and 2 is for illustrative purposes only and forms no part of the claimed design.
